UNITED STATES PATENT OFFICE.

CHARLES C. GARDNER, OF CEDAR RAPIDS, IOWA, ASSIGNOR OF FORTY-FIVE ONE-HUNDREDTHS TO PETER N. KIMES.

MAIL-BAG RECEIVING AND DELIVERING APPARATUS.

No. 921,226.

Specification of Letters Patent.

Patented May 11, 1909.

Application filed February 24, 1909. Serial No. 479,828.

To all whom it may concern:

Be it known that I, CHARLES C. GARDNER, a citizen of the United States of America, residing at Cedar Rapids, in the county of 5 Linn and State of Iowa, have invented certain new and useful Improvements in Mail-Bag Receiving and Delivering Apparatus, of which the following is a specification, reference being had therein to the accompanying 10 drawing.

This invention relates to mail bag receiving and delivering apparatus and the object thereof is to provide means in a manner as hereinafter set forth for receiving a mail bag 15 when thrown from a car and maintain the bag in a locked compartment to prevent unauthorized persons from obtaining the same.

The invention further provides in combination with the receiver as hereinbefore referred to, a catcher arranged in such relation 20 with the receiver that after the bag has been caught, it will be delivered to the receiver and automatically discharged into a locked compartment.

25 A further object of the invention is to provide a delivering device in a manner as hereinafter set forth for the bag so that the bag can be readily grabbed or caught by the catcher on the car and delivered therein.

30 Further objects of the invention are to provide an apparatus for receiving and delivering mail bags which shall be comparatively simple in its construction, strong, durable, efficient in its use, readily set up in 35 operative relation with respect to a railway track, and comparatively inexpensive to manufacture.

With the foregoing and other objects in view, the invention consists of the novel 40 construction, combination and arrangement of parts hereinafter more specifically described and illustrated in the accompanying drawings wherein is shown the preferred embodiment of the invention, but it is to be understood that changes, variations and 45 modifications can be resorted to which come within the scope of the claims hereunto appended.

In the drawings wherein like reference 50 characters denote corresponding parts throughout the several views, Figure 1 is a front elevation of a mail bag catcher, receiver and deliverer in accordance with this invention and set up in operative relation 55 with respect to a railway track. Fig. 2 is a

longitudinal sectional view of the receiver. Fig. 3 is a transverse section of the receiver also showing the same in operative relation with respect to the car, the latter being shown diagrammatically, Fig. 3 being a section on line 3—3, Fig. 1, looking in the direction of the arrow. Fig. 4 is a section on line 4—4, Fig. 1, looking in the direction of the arrow. Fig. 5 is a detail of one of the elements of the catcher, and, Fig. 6 is a detail 65 in plan of one of the arms of the deliverer.

Referring to the drawings by reference characters, 1 denotes the rails of a track and 2, a mail car adapted to travel thereon. The bottom of the car is indicated as at 3. 70

Arranged at one side of the track is a receiver referred to generally by the reference character 4 and consisting of a receptacle having a back wall 5, end walls 6, a front wall 7 and a bottom formed of a stationary 75 and pivoted section 8, 9, respectively. The front wall 7 is of less length than the receiver but of a height equal to the height of the receiver and in connection with the movable section 9 of the bottom when the latter is 80 tilted and with the end wall 6 forms a pocket 10 for the reception of the bag. The section 9 of the bottom of the receiver is connected at one side of its center as at 11 to a rock-shaft 12 journaled in the rear wall 5 and 85 front wall 7. The receptacle further comprises a dome-shaped top 13 and a ledge 14 which is mounted upon the supports 15 at the front of the receiver. The ledge 14 is positioned so that it will be on a level with 90 the floor 3 of the car. The stationary section 8 of the bottom of the receiver is concave in cross section and is inclined downwardly from the open end 16 of the receiver. The pivoted section 9 of the bottom of the 95 receiver when in its normal position overlaps the inner end of the section 8 as at 17 and the said section 9 at each side is provided with a vertical flange 18 and at one end with an upturned flange 19. Depending from the lower face of the section 9 at a point in proximity to the flange 19 is a catch 21 adapted, when the section 9 is tilted, to assume a vertical position as shown in Fig. 2, to engage with a counterweighted latch arm 22 pivoted upon 100 a support 23. The section 9 of the bottom also extends downwardly at an inclination.

Owing to the fact that the front wall 7 extends but part way of the length of the receiver, the latter is thereby formed with an 110

open front for a portion of its length as indicated at 24, (see Fig. 3) through which open front the mail bag is thrown so that it can drop upon the inclined bottom. As the bag 5 moves down the inclined bottom of the receiver it passes upon the section 9 of the bottom and when it has passed to a point beyond the rock-shaft 12, the weight of the bag will tilt the section 9 so that it will assume a 10 vertical position and form in connection with the end wall 6, the rear wall 5, and the front wall 7, the pocket 10 in which the bag is deposited. When the section 9 is tilted to a 15 vertical position, the catch 21 engages with the latch 22 and the section 9 is maintained in such vertical position. By such an arrangement the mail bag after it has been delivered to the receiver and deposited in the 20 pocket 10 is prevented from injury by in- clement weather or the bag cannot be reached by an unauthorized person. To allow of the removal of the bag from the pocket 10 after the same has been deposited therein, the rear wall 5 is formed with a door 25 25 hinged as at 26 and provided with a lock as at 27. When the door 25 is unlocked, it can be lowered so that the proper party can remove the mail bag or pouch from the section 19.

To prevent injury to the sack or bag and 30 also the contents thereof as the bag slides down the inclined bottom of the receiver, the inner face of the end wall 6 is provided with a cushion 28. After the bag or pouch has been removed from the pocket 10, the movable 35 section 9 of the bottom is released from the latch 22 and shifted back to the position shown in full lines in Fig. 1 so that the said section will again be in position to deliver the bag or pouch to the pocket 10.

40 The receiver has associated therewith a catcher which may be used when darkness or a storm prevents the mail clerk from throwing the bag or pouch into the receiver, the catcher grabbing the suspended bag from the car and delivering it into the receiver, the bag or pouch gliding down the inclined bottom of the receiver and being deposited by the movable section 9 into the pocket 10 in a manner as hereinbefore referred to.

45 The catcher comprises a post 29 which is positioned at one side of the open end of the receiver and to the post 29 is secured outwardly extending arms 30 and 31 which carry a vertically extending rod 32 provided 50 approximately centrally with an eye 33. Pivoted to the rod 32 is a yoke-shaped supporting member 34 having an eye 35 at its outer end. Extending through the eyes 33 and 34 is a catcher arm 36, the outer end of 55 which is formed with a hook 37. The inner end of the arm 36 terminates in a depending crank 38 which is pivotally connected as at 39 to the upper end of a vertically movable rod 40 which travels through the guides 41 60 carried by the post 29 and has secured to its

lower end the weight 42. The hook 37 of the arm 36 extends in a direction to receive the mail bag and as the bag is caught by the hook, the momentum carries the catcher arm 36 forwardly, swinging the yoke-shaped 70 member 34 on its pivot. The catcher arm 36 rotates so that the hook 37 is turned downwardly as shown in Fig. 5 and the bag is then discharged into the receiver and from there delivered into the pocket. The 75 weight 42 maintains the catcher arm 36 normally in extended position. When the yoke-shaped member 34 swings around, it is evident that the catcher arm 36 will rotate, such action lifting the weight 42 until 80 the crank 38 extends horizontally. As soon as the sack is discharged, the weight 42 draws the catcher arm back to its normal position.

The deliverer or crane which is arranged 85 in operative relation with respect to the closed end of the receiver, comprises a post 43 having a pair of suspension arms 44 and 45 pivoted thereto, these arms when not supporting a sack or pouch as shown in Fig. 90 4, drop down against the faces of the post 43. Each of the arms 44, 45 have connected thereto a supporting member 46 having diverging ends 47 which constitute fingers. Pivoted to each of the members 46 is a re- 95 taining arm 48 having its outer end curved as at 49 so as to extend over one of the fingers 47. Attached to the inner end of the arm 48 is a spring 50, the latter being also attached as at 51 to the member 46. The 100 curvilinear outer end of the arm 48 receives the ring of the mail sack and said arm is retained in position by the spring 50; the receiving arm carried by the car catches the sack and easily draws it from the holder as 105 will be evident.

What I claim is:

1. A mail bag receiver comprising a receptacle provided with an open front and an inclined bottom having a stationary and a 110 tilting section, said receptacle further provided with a pocket, one of the walls of said pocket formed by said tilting section when moved to a vertical position.

2. A mail bag receiver comprising a receptacle provided with an open front and an inclined bottom having a stationary and a tilting section, said receptacle further provided with a pocket, one of the walls of said pocket formed by said tilting section when 120 moved to a vertical position, said tilting section provided at one end with a flange, and means whereby access can be had to said pocket.

3. A mail bag receiver comprising a receptacle provided with an open front and an inclined bottom having a stationary and a tilting section, said receptacle further provided with a pocket, one of the walls of said pocket formed by said tilting section when 125 130

- moved to a vertical position, and means for maintaining said tilting section in a vertical position.
4. A mail bag receiver comprising a receptacle provided with an open front and an inclined bottom having a stationary and tilting section, said receptacle further provided with a pocket, one of the walls of said pocket formed by said tilting section when moved to a vertical position, said tilting section provided at one end with a flange, means whereby access can be had to said pocket, and means for maintaining said tilting section in a vertical position.
5. A mail bag receiver comprising a receptacle provided with an open front, inclined bottom and an open end, said bottom having a stationary and a tilting section, said receptacle further provided at one end with a pocket, one of the walls of said pocket formed by said tilting section when moved to a vertical position, combined with a catcher positioned in operative relation with respect to the said open end for discharging a bag in the receptacle.
6. A mail bag receiver comprising a receptacle provided with an open front, inclined bottom and an open end, said bottom having a stationary and a tilting section, said receptacle further provided at one end with a pocket, one of the walls of said pocket formed by said tilting section when moved to a vertical position, said tilting section provided at one end with a flange, and means whereby access can be had to said pocket, combined with a catcher positioned in operative relation with respect to the said open end for discharging a bag in the receptacle.
7. A mail bag receiver comprising a receptacle provided with an open front, inclined bottom and an open end, said bottom having a stationary and a tilting section, said receptacle further provided at one end with a pocket, one of the walls of said pocket formed by said tilting section when moved to a vertical position, and means for maintaining said tilting section in a vertical position, combined with a catcher positioned in operative relation with respect to the said open end for discharging a bag in the receptacle.
8. A mail bag receiver comprising a receptacle provided with an open front, inclined bottom and an open end, said bottom having a stationary and a tilting section, said receptacle further provided at one end with a pocket, one of the walls of said pocket formed by said tilting section when moved to a vertical position, said tilting section provided at one end with a flange, means for maintaining said tilting section in a vertical position, and means whereby access can be had to said pocket, combined with a catcher positioned in operative relation with respect to the said open end for discharging a bag in the receptacle.
9. A mail bag receiver comprising a receptacle having an inclined bottom opening into a pocket, said bottom formed of a tilting and a stationary section, said tilting section when moved to a vertical position constituting one of the walls of said pocket, said receptacle having an open front, the lower wall of the opening at the front of the receptacle being on a level with the floor of a mail car.
10. A mail bag receiver comprising a receptacle provided with an open front, inclined bottom and an open end, said bottom having a stationary and a tilting section, said receptacle further provided at one end with a pocket, one of the walls of said pocket formed by said tilting section when moved to a vertical position, and means for maintaining said tilting section in a vertical position, combined with a catcher positioned in operative relation with respect to the said open end for discharging a bag in the receptacle.
11. A mail bag receiver comprising a receptacle having an inclined bottom opening into a pocket, said bottom formed of a tilting and a stationary section, said tilting section when moved to a vertical position constituting one of the walls of said pocket, said receptacle having an open front, the lower wall of the opening at the front of the receptacle being on a level with the floor of a mail car, and means whereby access can be had to said pocket.
12. A mail bag receiver comprising a receptacle having a bottom opening into a pocket, said bottom formed of a tilting and a stationary section, said tilting section when moved to a vertical position constituting one of the walls of said pocket, said receptacle having an open front, the lower wall of the opening at the front of the receptacle being on a level with the floor of a mail car, combined with a catcher for delivering a mail bag to said receiver.
13. A mail bag receiver comprising a receptacle provided with an open front, a bottom and an open end, said bottom having a stationary and a tilting section, said receptacle further provided at one end with a pocket, one of the walls of said pocket formed by said tilting section when moved to a vertical position, and means for maintaining said tilting section in a vertical position, combined with a catcher positioned in operative relation with respect to the said open end for discharging a bag in the receptacle.
14. A mail bag receiver comprising a receptacle having an inclined bottom opening into a pocket, said bottom formed of a tilting and a stationary section, said tilting section when moved to a vertical position constituting one of the walls of said pocket, said receptacle having an open front, the lower wall of the opening at the front of the receptacle being on a level with the floor of a mail car, and means whereby access can be had to said

pocket, combined with a catcher for delivering a mail bag to said receiver.

15. A mail bag receiver comprising a receptacle provided with an open front and a bottom having a stationary and a tilting section, said receptacle further provided with a pocket, one of the walls of said pocket formed by said tilting section when moved to a vertical position, and a cushion within the receptacle at that end thereof provided with the pocket.

16. A mail bag receiver comprising a receptacle provided with an open front and an inclined bottom having a stationary and a tilting section, said receptacle further provided with a pocket, one of the walls of said pocket formed by said tilting section when moved to a vertical position, said tilting section provided at one end with a flange, means whereby access can be had to said pocket, and a cushion within the receptacle at that end thereof provided with the pocket.

17. A mail bag receiver comprising a receptacle provided with an open front and a bottom having a stationary and a tilting section, said receptacle further provided with a pocket, one of the walls of said pocket formed by said tilting section when moved to a vertical position, means for maintaining said tilting section in a vertical position, and a cushion within the receptacle at that end thereof provided with the pocket.

18. A mail bag receiver comprising a receptacle provided with an open front and an inclined bottom having a stationary and tilting section, said receptacle further provided with a pocket, one of the walls of said pocket formed by said tilting section when moved to a vertical position, said tilting section provided at one end with a flange, means whereby access can be had to said pocket, means for maintaining said tilting section in a vertical position, and a cushion within the receptacle at that end thereof provided with the pocket.

19. A mail bag receiver comprising a receptacle provided with an open front, inclined bottom and an open end, said bottom having a stationary and a tilting section, said receptacle further provided at one end with a pocket, one of the walls of said pocket formed by said tilting section when moved to a vertical position, combined with a catcher positioned in operative relation with respect to the said open end for discharging a bag in the receptacle, and a cushion within the receptacle at the closed end thereof.

20. A mail bag receiver comprising a receptacle provided with an open front, inclined bottom and an open end, said bottom having a stationary and a tilting section, said receptacle further provided at one end with a pocket, one of the walls of said pocket formed by said tilting section when moved to

a vertical position, said tilting section provided at one end with a flange, means whereby access can be had to said pocket, combined with a catcher positioned in operative relation with respect to the said open end for discharging a bag in the receptacle, and a cushion within the receptacle at the closed end thereof.

21. A mail bag receiver comprising a receptacle provided with an open front, inclined bottom and an open end, said bottom having a stationary and a tilting section, said receptacle further provided at one end with a pocket, one of the walls of said pocket formed by said tilting section when moved to a vertical position, means for maintaining said tilting section in a vertical position, combined with a catcher positioned in operative relation with respect to the said open end for discharging a bag in the receptacle, and a cushion within the receptacle at the closed end thereof.

22. A mail bag receiver comprising a receptacle provided with an open front and a bottom having a stationary and a tilting section, said receptacle further provided with a pocket, one of the walls of said pocket formed by said tilting section when moved to a vertical position.

23. A mail bag receiver comprising a receptacle provided with an open front and a bottom having a stationary and a tilting section, said receptacle further provided with a pocket, one of the walls of said pocket formed by said tilting section when moved to a vertical position, said tilting section provided at one end with a flange, and means whereby access can be had to said pocket.

24. A mail bag receiver comprising a receptacle provided with an open front and a bottom having a stationary and a tilting section, said receptacle further provided with a pocket, one of the walls of said pocket formed by said tilting section when moved to a vertical position, and means for maintaining said tilting section in a vertical position.

25. A mail bag receiver comprising a receptacle provided with an open front, a bottom and an open end, said bottom having a stationary and a tilting section, said receptacle further provided at one end with a pocket, one of the walls of said pocket formed by said tilting section when moved to a vertical position, combined with a catcher positioned in operative relation with respect to the said open end for discharging a bag in the receptacle.

26. In an apparatus of the class described, a crane consisting of a post, a pair of suspension arms pivoted thereto, a supporting member carried by each of the arms and having diverging ends to provide fingers, and spring-controlled retaining arms each having the outer end curved and extending over one

of the fingers of a supporting member, said retaining arms pivoted to said supporting members.

27. In an apparatus of the class described, 5 a catcher comprising a post, a vertically extending rod carried thereby, a yoke-shaped supporting member pivoted to said rod, a vertically movable weighted arm, and a catcher arm supported by said member hav-

ing its outer end formed with a hook and its 10 inner end formed with a crank connected to said vertically movable arm.

In testimony whereof I affix my signature in the presence of two witnesses.

CHARLES C. GARDNER.
